COFFEE MAKER

Dominic J. De Fano, River Grove, Ill., assignor to McGraw-Edison Company, Milwaukee, Wis., a corporation of Delaware

Filed Sept. 1, 1964, Ser. No. 81,546

Term of patent 14 years

(Cl. D44—26)

Fig. 1

FIG. 1 is an elevation view showing the front and left side of a coffee maker embodying my design; and FIG. 2 is an elevation view of the coffee maker of FIG. 1 showing the rear and right side thereof.

I claim:

The ornamental design for a coffee maker, as shown.
